UNITED STATES PATENT OFFICE.

MORTON T. KRESTELLER, OF SAN FRANCISCO, CALIFORNIA.

DESIGN FOR AN AUTOMOBILE SERVICE-CAR.

57,675.

Specification for Design.

Patented Apr. 26, 1921.

Application filed November 22, 1920. Serial No. 425,914. Term of patent 7 years.

To all whom it may concern:

Be it known that I, MORTON T. KRESTELLER, a citizen of the United States, and a resident of the city and county of San Francisco, State of California, have invented a new, original, and ornamental Design for an Automobile Service-Car, of which the following is a specification, reference being had to the accompanying drawings, forming part thereof.

Figure 1 is a side elevation and Fig. 2 is a plan view of the automobile service car, showing my new design.

I claim:

The ornamental design for an automobile service car, as shown.

MORTON T. KRESTELLER.
